US00D864761S

(12) **United States Design Patent** (10) **Patent No.:** **US D864,761 S**
Baker et al. (45) **Date of Patent:** **** Oct. 29, 2019**

(54) **CONTAINER**

- (71) Applicant: **Silgan Containers LLC**, Woodland Hills, CA (US)
- (72) Inventors: **Gerald J. Baker**, Wauwatosa, WI (US); **Rowdy H. Holstine**, Hartford, WI (US); **Jianwen Hu**, Oconomowoc, WI (US)
- (73) Assignee: **Silgan Containers LLC**, Woodland Hills, CA (US)
- (**) Term: **15 Years**
- (21) Appl. No.: **29/682,125**
- (22) Filed: **Mar. 1, 2019**

Related U.S. Application Data

- (60) Division of application No. 29/572,576, filed on Jul. 28, 2016, now Pat. No. Des. 847,661, which is a division of application No. 29/537,251, filed on Aug. 24, 2015, now Pat. No. Des. 766,112, which is a continuation of application No. 29/472,763, filed on Nov. 15, 2013, now Pat. No. Des. 739,266, which is a division of application No. 29/440,604, filed on Dec. 21, 2012, now Pat. No. Des. 696,594.

(57) **CLAIM**

We claim the ornamental design for a container, as shown and described.

DESCRIPTION

FIG. 1 is a perspective view of an embodiment of the claimed design;

FIG. 2 is a front view of the claimed design of FIG. 1, the rear view, the left side view, and the right side view being the same as the front view;

FIG. 3 is a top view of the claimed design of FIG. 1; and, FIG. 4 is a bottom view of the claimed design of FIG. 1. The broken lines shown are included for the purpose of illustrating portions of the container that form no part of the claim.

1 Claim, 3 Drawing Sheets
